UNITED STATES PATENT OFFICE.

WILLIAM KOCH, OF NEW YORK, N. Y.

DESIGN FOR A QUILTING OR EMBROIDERY PATTERN.

SPECIFICATION forming part of Design No. 16,726, dated June 8, 1886.

Application filed January 18, 1886. Serial No. 189,006. Term of patent 14 years.

To all whom it may concern:

Be it known that I, WILLIAM KOCH, a citizen of the United States, residing in the city, county, and State of New York, have invented and produced a new and original Design for Quilting or Embroidery Pattern, of which the following is a specification, reference being had to the accompanying drawings, and to the letters of reference marked thereon, making a part thereof, in which—

Figure 1 illustrates the principal feature of my design; Fig. 2, the complete design, and Fig. 3 the design extended.

The principal feature of this design is the character consisting of an ogee **A** (see dotted lines in Fig. 1) whose two semicircular curves, *b b'*, are of equal radii, terminating at one end in a straight line, *c*, equal in length to one-half the distance between the extremities of the ogee, and which extends in a direction coincident with the centers of the arcs described by its inner and outer curves.

The complete design consists of the series of characters **A A** disposed in double rows, as shown in Fig. 2, with the straight lines *c c* of all the characters in each row coinciding in their direction and bisecting each the ogee of the character next preceding it. The straight lines *c c* are parallel, and the opposite curves in the adjacent rows touch each other centrally, the relative position of the parallel straight lines being such as that an imaginary line, *x x*, con-

necting the two ends of the adjacent parallel lines in any two of the rows forms an angle with said lines of forty-five degrees, more or less, as shown in Fig. 3.

The design, when extended and enlarged, (see Fig. 3,) presents a multiplication in number of the double rows, following the arrangement last described, wherein a right line, *x x*, drawn to intersect the ends of the corresponding straight lines in two or more rows will form an angle of about forty-five degrees with said straight lines.

I claim as my invention—

The design for quilting or embroidery pattern herein shown and described, the same consisting of the double rows of ogees *b b'* and of the straight lines *c c*, each bisecting the first ogee and joining the second ogee next preceding it, the opposite curves *b b'* in the adjacent rows being in contact, and the several parallel straight lines in a relative position admitting of an intersection of their ends by an imaginary line, *x x*, drawn at an angle of about forty-five degrees therewith.

In testimony whereof I have signed my name to this specification in the presence of two subscribing witnesses.

WILLIAM KOCH.
